[57] **ABSTRACT**

An automated printing ink supply device including an ink storage container, a slider valve through which the flow of printing ink onto an ink receiving area can be controlled and a mechanism including a liquid level detector for operating the slider valve. By this means, the ink can be automatically supplied to the ink receiving area on the screen during the time an endless belt of the automatic screen printing machine is stopped to compensate for the amount of the printing ink that has been lost or deposited on the material to be printed.

SCREEN PRINTER WITH INK LEVEL SENSING AND CONTROL

The present invention relates to an automatic screen printing machine and, more particularly, to an improvement in an automatic screen printing machine wherein an automated printing ink supply device is provided for automatically supplying a proper amount of printing ink onto the screen to compensate for the amount of said ink that has been deposited on material to be printed.

Specifically, the present invention pertains to the automated printing ink supply device so designed as to maintain at a predetermined value the position of a liquid surface of the printing ink contained in an ink receiving area on the screen throughout the screen printing operation.

The automatic screen printing machine to which the present invention is applicable, in general, includes an endless belt made of hard or soft rubber material and adapted to carry a textile material to be printed which material is adhered to the upper flat surface of the forwardly moving, relative to the direction of movement of the material through the machine, run of said belt, said endless belt being intermittently moved so that, during the time it is standing still, a screen frame (or screen frames in the case of multi-colour printing) having a screen is downwardly shifted together with a pair of squeegees until the screen substantially contacts the textile material on the endless belt and said squeegees are subsequently traversed on the screen in the direction of the width of the belt and the machine proper to deposit a printing ink, which has been contained on the screen, onto the textile material through the screen to complete the ink depositing operation.

After the completion of the ink depositing operation at which time the pair of squeegees is normally transferred from the initial position to another position, the screen frame is upwardly shifted together with the squeegees and the endless belt is again moved, thus completing a cycle of squeegee movement.

Despite the fact that the printing machine carries out consecutive cycles of the ink depositing operation in an automatic manner, a primitive method has usually been employed to supply printing ink onto a printing ink receiving area on the screen in which an attendant worker utilizes a ladle-like instrument for supplying the printing ink from an ink storage container placed at one side of the machine proper. In multi-color screen printing, a storage container is naturally required for the screen frame for each color so that a number of attendant workers corresponding to the number of colors is usually required. If a single attendant worker is forced to take charge of supplying the printing ink of different color to, for example, three or four screen frames, he will be confused as to where to supply the printing ink of what color and, in an extreme case, will neglect to supply the printing ink of a specific color to one of the screen frames since each printing operation is carried out in a matter of seconds. If this event occurs, the textile material will have an unevenly color-printed appearance or will otherwise be spoiled.

As is well known to those skilled in the art, the printing ink usually employed has a relatively high viscosity ranging from about 4,000 to 90,000 c.p.s. and, accordingly, the weight of the printing ink imposed on a unit area of the screen, namely, the amount of the printing

ink normally contained in an ink receiving area on the screen, is one of the major factors that affect the success of the printing performance. For this reason, it is desirable to maintain at a constant value, the amount of the printing ink contained in the ink receiving area on the screen. However, this cannot be achieved by the above mentioned primitive method.

To eliminate the disadvantages inherent in the above mentioned primitive method of supplying the printing ink, there has been proposed an arrangement wherein a combination of a pumping device with a choke valve is provided for the this purpose. In this instance, the choke valve is normally positioned above the ink receiving area on the screen and the printing ink is continuously supplied through the choke valve onto the screen by the pumping device at a relatively low rate.

However, even this proposed arrangement has a disadvantage in that, in view of the fact that the ink receiving area on the screen is defined by the squeegees in co-operation with the screen frame, the printing ink contained therein begins to spread over the surface of the screen following the moving squeegee as the latter is traversed to another position away from the position where the choke valve is located and an excessive amount of the printing ink is, therefore, deposited on the textile material to be printed during each period the endless belt is stopped.

Accordingly, an essential object of the present invention is to provide an automated printing ink supply device for use in screen printing machines which is capable of supplying a proper amount of printing ink onto the ink receiving area on the screen to compensate for the amount of said ink that has been lost or deposited on the textile material to be printed.

Another object of the present invention is to provide an automated printing ink supply device for use in screen printing machines which includes a slider valve having a passage one end of which communicates with an ink storage container and the other end of which is directed to the ink receiving area, said slider valve being so designed as to permit the flow of printing ink onto the ink receiving area without any formation of droplets of ink about said other end which may unnecessarily waste the ink and/or contaminate portions of the machine.

A further object of the present invention is to provide an automated printing ink supply device for use in screen printing machines wherein a slider valve is provided which is operable by the logical product of electrical signals, one of which is fed from a liquid level detector and which is representative of a deviation of the position of the liquid surface of the printing ink contained in the ink receiving area relative to a predetermined position and the other of which is fed from a limit switch or electromagnetic device and which is representative of the return of the squeegees from a position remote from the ink supply device, whereby a proper amount of printing ink can be supplied onto the ink receiving area only when the liquid surface position of the printing ink is lowered beyond the predetermined position while the squeegees is completely returned to the initial position adjacent to the ink supply device.

A still further object of the present invention is to provide an automated printing ink supply device for use in screen printing machines wherein means is provided for operating the slider valve to permit the flow

of the printing ink from the ink storage container onto the ink receiving area to maintain at a predetermined value the amount of the printing ink contained in the ink receiving area on the screen.

A still further object of the present invention is to provide an automated printing ink supply device for use in screen printing machines wherein a printing ink storage container is movably supported whereby transportation of the ink storage container from the printing position to another or a preparation room where the printing ink is prepared can be facilitated.

A still further object of the present invention is to provide an automated printing ink supply device for use in screen printing machines which contributes to the reduction of the number of attendant workers in charge of ink supply stations for each screen printing machine without causing any situation such as that in which an attendant worker has heretofore been often-times confused as to where to supply printing ink of what color.

A still further object of the present invention is to provide an automated printing ink supply device for use in screen printing machines which contributes to the reduction of labour cost and is effective to produce printed textile material at low cost as compared with the labour cost that has been incurred by the employment of a number of attendant workers.

These and other objects and features of the present invention will become apparent from the following full description of the present invention taken in conjunction with preferred embodiments thereof with reference to the accompanying drawings, in which;

FIG. 1 is a schematic side view of an exemplary type of screen printing machine arrangement to which the present invention is applicable,

FIG. 2 is a schematic diagram showing a carriage structure for movably supporting the printing ink storage container,

FIG. 21 is a top plan view of FIG. 19, and

FIG. 22 is a schematic diagram showing the arrangement of rails in the printing shop for the over-head carriage arrangement of FIG. 19.

Before the description of the present invention proceeds in connection with preferred embodiments thereof with reference to the accompanying drawings, it is noted that like parts are designated by like reference numerals throughout the accompanying drawings.

Referring now to FIG. 1, the automatic screen printing machine generally comprises a supply unit I, a printing unit II and a take-up and drying unit III. This automatic screen printing machine further includes an endless belt A adapted to be circulated round a pair of belt drums 1 and 2, one of which is accommodated in the supply unit I and the other of which is accommodated in the printing unit II at a position remote from the supply unit. As shown, this endless belt is deflected substantially at right angles by a pair of deflection rollers 3 and 4 from the vertical run to the horizontal run. The belt A is adapted to be driven by the roller 3 or another roller (not shown) disposed at a suitable position, which is in turn drivingly connected with a suitable motor. The drive roller 3 has a counter pressure roller 5, around which material to be printed, for example, cloth B, is fed from a roll C of cloth by means of a deflection roller 6. The cloth B passes through the contact point between the drive roller 3 and the counter pressure roller 5 and is usually, as known to those skilled in the art, adhered to the adjacent surface of the endless belt A on which an adhesive agent has been spread by means of a gluing roller 7 positioned below the drive roller 3 and behind the counter pressure roller 5 with respect to the feed direction of the cloth B.

The drive roller 3 may be driven either continuously or intermittently. However, the printing operation requires that the endless belt A stand still relative to ink depositing means for a short time, during which a single screen frame or a plurality of screen frames D are moved downwardly to enable an ink depositing operation to be performed. Accordingly, in the case where the ink depositing operation is to be performed while the drive roller 3 is continuously driven such as shown in FIG. 1, both drums 1 and 2 are adapted to move together in one direction. In other words, while the drive roller 3 is continuously driven, the drum 1 moves from a downwardly shifted position as indicated by the dotted line to an upwardly shifted position to take up the length of the endless belt A fed by the drive roller 3 toward the drum 1 and, at the same time, the drum 2 moves toward the supply unit I the same distance as the drum 1 is moved, so that the portion of the belt A situated in the printing unit II will be at the stand-still position relative to the screen frames D.

In any event, during the stand-still of the endless belt A, each screen frame D is moved from an upwardly

shifted position to a downwardly shifted position in which the cloth B on the belt A is closely covered with a screen carried by the screen frame D. At this time, a pair of spaced parallel squeegees is moved over the screen in the widthwise direction of the cloth B to deposit a printing ink on the flat surface of the cloth B through the screen and, thereafter, the screen frame D is moved to the upwardly shifted position together with the pair of the squeegees to complete the ink depositing operation.

The cloth B that has been printed during its travel through the printing unit II is separated from the belt A at the end of the printing unit II and is fed into the take-up and drying unit III in which the printed cloth is dried and rolled up.

The structure of the automatic screen printing machine so far described may be any conventional type such as that manufactured by Fritz Buser AG of Switzerland and, accordingly, the details thereof are herein omitted for the sake of brevity. More specifically, the present invention pertains exclusively to the printing unit II of the automatic screen printing machine and is directed to the automation of a printing ink supply system. A portion of said printing unit II to which the present invention is applicable is illustrated particularly in FIGS. 2 through 4 on an enlarged scale.

Referring now to FIGS. 2 through 4, the automated printing ink supply device according to the invention generally includes a bucket-like ink container E in which a proper amount of printing ink is contained, a solenoid operated valve assembly F for adjustably controlling the flow of printing ink from the container E onto a screen 10 (FIG. 3) carried by a screen frame D composed of a pair of sections 11 extending transversely of the belt A and a pair of sections 12 extending longitudinally of the belt A, all of which are arranged in a rectangular shape, and a carriage structure G for transporting the ink container E in the lengthwise direction of the machine proper.

The bucket-like ink container E comprises a generally cylindrical barrel portion 13 having a funnel-shaped bottom 14 with a circular depending flange around the central opening to define an opening 15. An annular flange 16 is integrally joined to the lowermost end of the barrel portion 13 and having a length greater than the height from the bottom edge of the opening 15 to the upper peripheral edge of the bottom 14. A handle portion 17 is provided at the top of the barrel portion 13.

The carriage structure G for transporting the ink container E in the lengthwise direction of the machine proper to bring the container E to a printing position where the screen frame D is positioned comprises a pair of vertically spaced parallel guide rails 18a and 18b rigidly secured to one side panel 18 of the machine proper, a pair of substantially horizontally elongated chassis members 19a and 19b, each having a pair of grooved rollers 20a and 20b rotatably on the ends thereof respectively the upper chassis 19a being adapted to be guided along the upper guide rail 18a by the pair of the grooved rollers 20a while the lower chassis 19b is adapted to be guided along the lower guide rail 18b by the pair of the grooved rollers 20a. A vertically upstanding supporter stud 21 has the lower end portion and the intermediate portion rigidly connected respectively with the chassis 19b and 19a, and a swing table 22 is pivotally connected with the upper free end

of the supporter stud 21 substantially at right angles thereto by means of a suitable bearing 23. This swing table 22 is rotatable about the axis of the supporter stud 21 through 360°, alternatively, between two angularly spaced positions, in one of which the flanged opening 15 of the container E, when it is mounted on this swing table 22, is positioned above the screen 10 and the other in which the flanged opening 15 is positioned laterally beyond the side panel 18 of the machine proper, as shown in FIG. 4. Connected between the bearing 23 and the swing table 22 is a substantially triangular reinforcement member 24 for preventing the table 22 from bending downwardly, which might occur when an excessively heavy load is imposed on the upper surface of said table 22.

As shown in FIG. 4, the swing table has two openings 25 and 26, one of which is positioned substantially in register with the flanged opening 15 of the container E when the container is mounted on the table 22 and the other of which is positioned between the first mentioned opening 25 and a point on the peripheral edge of a circular area of the table 22 occupied by the container E. This table 22 also has on its upper surface two or more projections 22a engageable with portions of the inner peripheral surface of the annular flange 16 of the container E for preventing the latter from being accidentally displaced from a predetermined position on the table 22.

Referring particularly to FIGS. 3 and 4, the screen frame D includes, in addition to the screen 10, a pair of squeegees 27a and 27b of any known construction. However, in the instance as shown, each of the squeegees 27a and 27b comprises a rubber blade, 28a and 28b respectively, and a blade holder, 29a and 29b respectively, having a lower end connected with the rubber blade in any known manner and the other end preferably outwardly bent with respect to the corresponding end of the opposite blade holder. As is well known to those skilled in the art, these squeegees 27a and 27b are alternately reciprocated in such a manner that, during one cycle of printing which begins when the screen frame D is downwardly shifted and ends when the frame D is upwardly shifted, one of the squeegees which is positioned rearwardly of the other with respect to the direction of movement of the squeegees during the one cycle of printing is moved from one position to another to deposit the printing ink on the cloth B on the belt A through the screen 10 while the other squeegee is raised clear of the screen and, during the following cycle of printing, said other squeegee is moved from said another position to the initial position to deposit the printing ink on the cloth B on the belt A through the screen 10 while said one squeegee is raised clear of the screen. Of course, during each cycle of printing, the belt A is standing still relative to the printing means as hereinbefore described and, after each period of standing still the belt A with the cloth B sticking to it is moved a distance to transfer a printed area of the cloth from one position to the next position.

A traversing movement of the squeegees 27a and 27b in one direction is normally effected at one position each time the screen frame D is downwardly shifted.

For convenience of description, it is assumed that the two positions between which a pair of the squeegees 27a and 27b travels during a reciprocating traversing movement are referred to as an "initial position" in which said pair of the squeegees is positioned adjacent

to the automated printing ink supply device or the supporter stud 21 and a "terminating position" which is remote therefrom. FIGS. 3 and 4 illustrate the squeegees 27a and 27b in their initial position, i.e., at the completion of their travel from the terminating position (not shown) remote from the supporter stud 21 to the initial position adjacent to the supporter stud 21.

While in the arrangement as hereinbefore described, a proper amount of printing ink which is usually composed of an adhesive agent, oil, an emulsion, pigment, dye stuffs, catalyst and other additives and which has a viscosity of from 4,000 to 90,000 c.p.s. is normally contained in an area defined by one of the squeegees 27a, one of the longitudinally extending sections 12 of the screen frame D which is adjacent to the supporter stud 21 and the screen. As is well known to those skilled in the art, the amount of the printing ink contained in that area has a tendency to decrease little by little as the squeegees 27a and 27b which are alternately brought into the operative position as hereinbefore described are reciprocated between the initial and terminating positions substantially across the width of the machine proper, since the printing ink is deposited through the screen 10 onto the flat surface of the cloth B lying on the endless belt A.

Accordingly, the automated printing ink supply device is herein provided for supplying a proper amount of the printing ink onto the above mentioned area to compensate for the ink being used up. Although the supply of the printing ink may be directed to any point within said area, namely, the flanged opening 15 of the container E may be positioned at any position above said area, it is preferable to direct the opening 15 at the central point of a portion of the area which is defined by the pair of the squeegees 27a and 27b and the screen 10 substantially as shown in FIG. 4. In other words, the swing table 22 is preferably rotatable about the axis of the supporter stud 21 from a first position in which the flanged opening 15 of the container E when mounted on the table 22 is in register with the central point substantially equally spaced from the ends of the squeegees 27a and 27b and midway between the pair of squeegees, to a second position in which the container E mounted on the table 22 is in a position clear of the machine proper.

The area defined by one of the squeegees 27a, one of the longitudinally extending sections 12 of the screen frame D which is adjacent to the supporter stud 21 and the screen 10 when said squeegees 27a and 27b are in the initial position and into which the printing ink is supplied as hereinbefore described is hereinafter referred to as the "ink receiving area."

The carriage structure G may be provided with a locking or braking device for stopping the carriage structure G at any desired position with respect to the machine proper. For example, a threaded bolt-like stop may be utilized for this locking or braking device. In this case, the threaded bolt-like stop may have a handle on one end and the other end extending through the supporter stud 21 and terminating at the side panel of the machine proper so that, when the handle is turned until the other end of said stopper contacts the side panel of the machine proper, the carriage structure G can be fixed at one position. However, since this locking or braking device may be of any known structure and can be easily provided by those skilled in the art, the details thereof are herein omitted and not shown.

The solenoid operated valve assembly F operable to supply the printing ink to the ink receiving area on the screen 10 only when the amount or surface level of the printing ink in the ink receiving area decreases to the value lower than a predetermined value includes a slider valve 30 having a construction which will be described later and which is tightly connected to the flanged opening 15 of the container E, an electromagnetic device 31 rigidly secured to the undersurface of the swing table 22 for operating the slider valve 30, a limit switch 32 operable in response to the vertical reciprocation of either of the squeegees 27a and 27b, and a liquid level detector 33 capable of detecting the position of a liquid surface of the printing ink contained in the ink receiving area, which may be conveniently interpreted as indicating the volume of the printing ink, and concurrently feeding an electrical signal representative of the position of the ink surface to the electromagnetic device 31, said electromagnetic device 31 being adapted to be operated so as to open the slider valve 30 according to the logical product of the electrical signal fed from the limit switch 32 and that from the liquid level detector 33.

The details of this solenoid operated valve assembly F are clearly shown in FIGS. 5 through 9. However, to begin with, the structure of the slider valve 30 will be hereinafter fully described particularly with respect to FIGS. 8 and 9.

The slider valve 30 as shown comprises a framework 30a of substantially rectangular shape having a pair of long sections and a pair of short sections, a lower plate member 30b of the same width as that of the framework 30a and having substantially at the central portion thereof an opening 30c, said lower plate member 30b being rigidly mounted on an intermediate portion of the framework 30a. An upper mounting plate member 30d having the same size as the lower plate member 30b and having an opening 30e in alignment with the opening 30c of the lower plate member 30b is mounted on framework 30a above lower plate member 30b and an annular flange 30f is provided on the upper surface of said mounting plate member 30d and surrounding said opening 30e. A pair of legs (not visible) each having substantially the same thickness as that of the corresponding long section of the framework 30a is rigidly connected with said respective long sections of the framework 30a between the upper and lower mounting plate members so that a clearance is formed between the under surface of said upper mounting plate member 30d and the upper surface of the lower plate member 30b. An intermediate slidable plate member 30h is slidably accommodated in said clearance and has an opening 30i therein of the same diameter as that of the opening 30c of the lower plate member 30b, and an adjustment screw 30j is adjustably threaded through a central portion of the first one of the short sections of the framework 30a for adjusting the positioning of the intermediate slidable plate member 30h as will be described later.

The intermediate slidable plate member 30h has one end downwardly bent to form a lever 30k and the other end connected with the other short section of the framework 30a by means of a tension spring 30m adapted to pull said slidable plate member 30h in the direction away from the adjustment screw 30j. In other words, while the openings 30c and 30e are in alignment with each other, the opening 30i of the slidable plate

member 30h is normally displaced from these openings 30c and 30e in which condition the valve 30 is closed.

The adjustment screw 30j includes a lock nut 30n provided for fixing the position of the adjustment screw 30j to set the degree of opening of the valve 30 by setting the limit of movement of the intermediate slidable plate member 30h. Although the limit of movement of the plate member 30 can be fixed by turning the adjustment screw 30j without it being necessary to provide a lock nut 30n, the lock nut acts to prevent the adjustment screw 30j from being loosened under the influence of, for example, vibration which may result in a change in the degree of opening of the slider valve 30.

When constructing this valve 30, care must be taken that the width and thickness of the slidable plate member 30h is such that it will be slidably accommodated in the clearance without permitting any possible leakage of fluid medium, such as printing ink that has been supplied to the opening 30e, from a gap between the undersurface of the mounting plate member 30d and the upper surface of the slidable plate member 30h or between the undersurface of said slidable plate member 30h and the upper surface of the lower plate member 30b.

These openings 30e, 30i and 30c when in registration with one another constitute a fluid passage through the slider valve 30, the degree of opening of said passage being adjustable in response to the position of said intermediate slidable plate member 30h at its limit of movement toward adjustment screw 30j which may be set by adjusting the adjustment screw 30j. It is to be noted that, although each of these openings 30e, 30i and 30c has been illustrated as having a circular shape, various shapes such as that of a triangle, oval and a combination of these shapes other than a circular shape may be advantageously employed without any reduction of the performance of the slider valve 30 herein described.

The upper mounting plate member 30d is provided with the circular flange 30f as hereinbefore described. This circular flange 30f has an inner diameter equal to the diameter of the opening 30e of the member 30d and substantially equal to the outer diameter of the flanged opening 15 of the container E so that the slider valve 30 can be connected with said flanged opening 15 of the container E in a fluid tight manner by means of a suitable fastening means.

From the foregoing description, it will be clearly understood that the printing ink contained in the container E can be discharged through the opening 15 when the slidable plate member 30h of the slider valve 30 is moved against the tension spring 30m, the flow of said ink from the container E through the valve 30 being cut off without any formation of drops of the printing ink about the opening 30c of the lower plate member 30b when the slidable plate member 30h is returned to the initial position by the action of the tension spring 30m. If a plurality of screws or bolts and nuts are employed for fastening the lower and upper plate members 30b and 30d to the framework 30a such as shown in FIG. 9, the slider valve 30 of the construction as hereinabove described can be easily disassembled and re-assembled without any loss of accuracy of the fit of the various parts thereof.

Referring now back to FIGS. 5 through 7, the slider valve 30 is mounted on the container E in a manner as shown in FIG. 5 and FIG. 6. This valve 30 is, as herein-

before described, adapted to be operated by the electromagnetic device 31 secured to the undersurface of the swing table 22.

This electromagnetic device 31 includes a solenoid 5 operated piston rod 31a having one end slidably mounted within the electromagnetic device and the other end connected with the lever 30k of the intermediate slidable plate member 30h. The connection between the said other end of the piston rod 31a and the 10 lever 30k of the slidable plate member 30h includes a link member 34 pivotally mounted on pivot 34a on the swing table 22 and having one end connected with the said other end of the piston rod 31a through a tension spring 35 exerting a tension force greater than that of the spring 30m in the valve 30, and having a roller 30 rotatably mounted on the other end (FIG. 5) which extends upwardly through the opening 25 and engages the lever 30k on the slidable plate member 30h of the slider valve 30. Disposed between the portion of the 15 link member 34 adjacent to the roller and the swing table 22 is a tension spring 37 for pulling the link member 34 so as to maintain the piston rod 31a in a first position when the electromagnetic device 31 is not excited, FIG. 7 showing the piston rod 31a in its second position when the electromagnetic device 31 is excited. However, the strength of this tension spring 37 is less than that of the tension spring 35 and substantially equal to or slightly greater than that of the tension spring 30m of the slider valve 30, so that, when the 20 electromagnetic device 31 is not excited, the link member 34 can be quickly rotated about the pivot 34a by the spring 35 to enable the piston rod 31a to return to the first position and concurrently to cause the intermediate slidable plate member 30h to be instantaneously moved in the direction of the tension in tension spring 30m. Since the slidable plate member 30h can be advantageously instantaneously moved to the position in which the slider valve 30 is closed, it will be 25 clearly understood that the slider valve 30 of the above construction will not permit formation of drops of the printing ink about the opening 30c of the lower plate member 30b because of the action of the plate 30k in slicing through the stream of liquid flowing through the slider valve.

Reference numeral 38 designates a stroke limiter for restricting the angular movement of the end of the link member 34 connected with the tension spring 35, which may be omitted if the stroke of movement of the piston rod 31a is sufficient to close and open the slider valve. It is to be noted that as shown in FIGS. 5 and 7 the parts are in positions in which the electromagnetic device 31 is excited and that the slider valve 30 is therefore in the open position to permit the flow of the printing ink from the container E onto the ink receiving area on the screen 10.

Disposed below the undersurface of the swing table 22 is a limit switch 32 rigidly fixed to a plate member 39 which is in turn rigidly connected with the undersurface of said swing table 22. This limit switch 32 is operable in response to the upward movement of either of the squeegees 27a and 27b which normally accompanies the upward movement of the screen frame D. However, as long as the limit switch 32 is disposed such that it can be switched on each time the pair of the squeegees 27a and 27b is returned to the initial position and/or the pair of squeegees 27a and 27b in the initial position is moved upwardly together with the screen 60 65

frame D, and as long as it is switched off when said pair of squeegees 27a and 27b is moved to the terminating position and/or said pair of squeegees 27a and 27b is downwardly shifted together with the screen frame D, respectively, this switch 32 may be connected in any known manner.

In the instance as shown, for operating the limit switch 32, the blade holder 29b of the squeegees 27b which is, when it is in the initial position, positioned rearwardly of the other squeegee 27a relative to the direction of advance thereof to the terminating position, has mounted on its top an umbrella-like operating member 40 which includes a vertical rod 40a and a substantially horizontally elongated member 40b. The limit switch 32 includes means responsive to the position of the squeegees and the frame in the form of an actuator 41 having a roller 41a rotatably mounted on the free end thereof engageable with the elongated member 40b of the operating member 40 in response to the presence of the squeegees 27a and 27b in position beneath the container E and the raising of the frame D.

In the arrangement as hereinbefore described, when the screen frame D is shifted upwardly immediately after the pair of the squeegees 27a and 27b has completed its return travel from the terminating position to the initial position at which position the squeegees 27a and 27b are in the positions as shown in FIG. 6, the operating member 40 mounted on the top of the blade holder 29b of the squeegee 27a pushes the roller 41a upwardly to turn the actuator 41 about its pivot so that the limit switch 32 can be switched on. This limit switch 32 that has been switched on is automatically switched off when the actuator 41 is turned in the opposite direction about its pivot, which occurs when the operating member 40 is retracted as squeegee 27b moves downwardly.

The liquid level detector 33 is an ultrasonic type detector and is mounted on either of the squeegees 27a and 27b, preferably, the squeegee 27a, so that it can be positioned between the two squeegees for detecting the position of the surface of the printing ink contained in the ink receiving area on the screen 10, and more particularly, can detect the position of the surface of the ink in the portion of the ink receiving area which is defined between the pair of the squeegees 27a and 27b and the screen 10 such as clearly shown in FIG. 6. This ultrasonic liquid level detector 33 is adapted, as hereinbefore described, to generate, only when the position of the ink surface in that portion of the ink receiving area becomes lower than a predetermined level, namely, when the volume of the ink in that portion of the ink receiving area is reduced to a value smaller than the predetermined value, an electrical signal which may be utilized to excite the electromagnetic device 31 as will be described later. Such detectors are well known, a preferred one being that sold by Delavan Manufacturing Co., West Des Moines, Iowa under the trademark SONAC.

The limit switch 32 and the ultrasonic liquid level detector 33 are connected in series with each other so that the electromagnetic device 31 can be excited only when electrical signals are generated at the same time from both devices. For example, an electrical circuit as shown in the right-hand portion of FIG. 10 may be employed wherein LS and DS indicate the limit switch 32 and the detector switch incorporated in the detector 33, respectively. From FIG. 10, it will be clearly under-

stood that, assuming that the main switch MS connecting the circuit to the power source is closed, when both switches LS and DS are closed at the same time, i.e., when a signal which is the logical product of the signals from the limit switch 32 and detector 33 is generated, a relay switch RS is closed so that the solenoid coil SC of the electromagnetic device 31 is excited thereby to open the slider valve 30.

Instead of an ultrasonic type detector, the liquid level detector 33 may be a float type such as shown in FIG. 11. In this case, a ball or cylindrical float 33a floating on the surface of the printing ink contained in that portion of the ink receiving area defined by the pair of squeegees 27a and 27b and the screen 10 should be arranged such that the up and down movement of said float 33a is transmitted to the detector switch DS having an actuator 33b for operating said switch DS. Naturally, the up and down movement of said float 33a is effected in response to the volume of the printing ink contained in that portion of the ink receiving area.

In the arrangement of the automated printing ink supply device as hereinbefore described, it will be clearly understood that when the printing ink contained in the ink receiving area on the screen 10 is consumed as a result of its being deposited on the flat surface of the cloth B lying on the endless belt A during the consecutive printing operations, the slider valve 30 will automatically be placed in the open position by the electromagnetic device 31 to permit the flow of an amount of the printing ink from the container E onto that portion of the ink receiving area sufficient to compensate for the amount of the printing ink consumed. Thus, it will, accordingly, be clearly understood that the level of the surface of the printing ink in the ink receiving area can be maintained at a constant value throughout the printing operation.

Although in the foregoing arrangement the slider valve 30 has been described as operated by the electromagnetic device 31, mechanical means for operating said valve 30 can be employed, such as shown in FIGS. 12 through 15. Hereinafter, the mechanical arrangement for operating said slider valve 30 will be described with reference to FIGS. 12 through 15.

Referring to the drawings, it will be understood that a major portion of the arrangement shown is substantially the same as shown in FIGS. 5 and 7. However, the electromagnetic device 31 shown in FIGS. 5 and 7 is replaced as will be hereinafter mentioned. The mechanical means for operating said slider valve 30 includes a mounting bracket 42 having one end rigidly connected with the undersurface of the swing table 22 and the other end having thereon a shaft 43 on which is rotatably mounted one end of an elongated supporting strip 44. This elongated supporting strip 44 is provided at its other end with a connecting member 45 having a substantially inverted L-shape and being rotatably connected at the intermediate bending point 45a with said free end of said strip 44. This connecting member 45 is provided at its one end with a roller 45b engageable with an engagement member 12a mounted on the longitudinally extending short section 12 of the screen frame D so that the connecting member 45 can be rotated, as viewed in FIG. 12 or 15, in the clockwise direction as said roller 45b is engaged by the upwardly moving frame D, the other end of said connecting member 45 being connected with the adjacent end of the tension spring 35 by a connecting piece 46.

The supporter strip 44 is normally urged in the direction toward the squeegees 27a and 27b by mean of a return spring 47 having one end rigidly connected with a portion of the mounting bracket 42 and the other end connected with a portion of the strip 44 adjacent to the shaft 43 so that the roller 45b of the connecting member is normally disengaged from the engagement member 12a on the screen frame D. This supporting strip 44 has at its intermediate portion an integral tongue-like member 44a which is supported as will be mentioned later.

As clearly shown in FIG. 15, also suspended from the undersurface of the swing table 22 is a substantially L-shaped rigid member 48 having a horizontally extending free end having a pair of spaced downwardly extending fingers 48a and 48b thereon extending on the opposite sides of said tongue-like member 44a on the supporter strip 44. These fingers 48a and 48b serve as a stroke limiter and are respectively provided with adjustments screws 48c and 48d threaded therethrough and which are adjustable for defining the stroke of movement of the tongue-like member 44a, and thereby the stroke of the supporter strip 44.

Disposed at the said other end of the supporter strip 44 and extending laterally thereof is an electromagnetic device 49 housed in a casing 49a rigidly supported by said free end of said supporter strip 44, said electromagnetic device 49 including a collapsible piston member 49b extending out of said casing 49a toward the squeegees 27a and 27b. This electromagnetic device 49 is electrically associated with the liquid level detector 33 so that the piston member 49b, which is normally retracted, will be projected outwardly upon excitation of the electromagnetic device 49 by an electrical signal from the liquid level detector 33 through amplifier A when the level of the surface of the printing ink in the ink receiving area fall below the predetermined value.

For pivoting the supporter strip 44 about the pivot 43 thereby to bring the roller 45b into engagement with the engagement member 12a on the screen frame D upon return of the squeegees 27a and 27b to the initial position, there is provided a feeler strip 50 having one end hinged, at 51, to a plate member 51a mounted on the casing 49a of the electromagnetic device 49, the other free end of said feeler strip 50 being adapted to be abutted by a portion of the adjacent squeegee 27b. This feeler strip 50 is normally pulled toward the electromagnetic device 49 by a tension spring 52 disposed between the plate member 51a and the feeler strip 50 so that said feeler strip 50 is constantly contacted by the tip of the piston member 49b.

With the arrangement shown in FIGS. 12 through 15, when the liquid level detector 33 generates and supplies to the electromagnetic device 49 an electrical signal indicating that the level of the surface of the printing ink in the ink receiving area has fallen below the predetermined value, the piston member 49b of the electromagnetic device 49 is projected outwardly thereby to cause the feeler strip 50 to rotate about the hinge 51 against the tension of spring 52 to an operative position in which the lower free end thereof can be abutted by a portion of the adjacent squeegee 27b when the latter is returned to the initial position. When the lower end of said feeler strip 50 is abutted by the squeegee 27b while the piston member 49b is in the outwardly projected position, the supporter strip 44

commences to pivot about the hinge 43 in the clockwise direction (as viewed in FIG. 13) carrying the electromagnetic device 49, whereby the roller 45b on the connecting member 45 is brought into position above the engagement member 12a on the screen frame D. When the screen frame D is subsequently upwardly shifted, the connecting member 45 is rotated about the pivot 45a with the roller 45b in engagement with the engagement member 12a so that the link member 34 is rotated about the pivot 34a in the counterclockwise direction (as viewed in FIG. 14) thereby to open the slider valve 30.

The condition as hereinbefore described will be maintained until the screen frame D is downwardly shifted together with the engagement member 12a to permit the connecting member 45 to rotate about the pivot 45a in the opposite direction so that the link member 34 will be rotated about the pivot 34a thereby to close the slider valve 30. In the event that the time during which the screen frame D is upwardly shifted is longer than the time necessary for supplying sufficient printing ink onto the ink receiving area on the screen 10, the slider valve 30 will be closed when the level of the surface of the printing ink in the ink receiving area rises to the predetermined level at which time the liquid level detector 33 ceases to generate the electrical signal supplied to the electromagnetic device 49. When the electromagnetic device 49 is deenergized, the piston member 49b is retracted to permit the feeler strip 50 to return to the initial position by the action of the tension spring 52 and concurrently to permit the supporter strip 44 to swing to a position where the roller 45b is disengaged from the engagement member 12a on the screen frame D.

Although in the foregoing embodiments the container E has been described as mounted on the swing table 22, it may be disposed on the floor, such as is shown in FIGS. 16 through 18, and a pumping device can be provided, as will be described hereinafter.

In the arrangement as shown in FIGS. 16 and 17, the container E may be of any conventional construction without the flanged opening 15 in the bottom. The container E is placed on the floor, the upper mounting plate member 30d of the slider valve 30 (FIGS. 8 and 9) is connected with a nozzle 53a of a valve 53 through the circular flange 30f. Particularly as shown in FIG. 17, this valve 53 has a pair of ports 53b and 53c communicating with each other, one of which is connected with the container E through the hydraulic pump 54 by means of a supply conduit 55a preferably made of flexible tubing and the other end connected with the container E directly through a return conduit 55b made of flexible tubing.

In the arrangement shown in FIGS. 16 and 17, the printing ink contained in the container E is adapted to be circulated by the pump 54 through the supply conduit 55a and then through the return conduit 55b via the valve 53 throughout the consecutive periods of the printing operation. However, once the slider valve 30 is opened in the manner as hereinbefore described, a portion of the printing ink thus circulated can be supplied onto the ink receiving area on the screen through the nozzle 53a of the valve 53.

In the arrangement shown in FIG. 18, the slider valve 30 is adapted to be directly operated by an electromagnetic device 56 while above the slider valve the supply unit I that has been the container E in the foregoing

embodiments shown in FIGS. 2 through 15 is a supply device 57 having a substantially V-shaped configuration. Also omitted is the swing table 22. The electromagnetic device 56 is rotatably mounted on the top of the supporter stud 21 and includes therein a solenoid coil 56a which is connected in series with the detector switch DS of the liquid level detector 33 and a piston member 56b having one end situated within the electromagnetic device 56 and the other end connected with the lever 30k of the intermediate slidable plate member 30h of the slider valve 30, said piston member 56b being normally urged by a compression spring 56c in the same direction as said slidable member 30h is pulled by the tension spring 30m of the slider valve 30.

The ink supply device 57 with the substantially V-shaped configuration comprises a cylindrical portion 57a, the lower end of which is connected to or integrally formed with the flange 30f of the mounting plate member 30d of the slider valve 30, and a conduit 57b having one end connected with the container E through a hydraulic pump 54 by means and a flexible tubing 58 and the other end communicating with the interior of the cylindrical portion 57a at a position adjacent to the lower extremity thereof. Slidably disposed within the cylindrical portion 57a is a piston rod 57d at one end a handle knob 57e situated outside the cylindrical portion 57a, and at the other end a plunger 57f, said piston rod 57d being normally urged in the downward direction by a compression spring 57g disposed between an upper end of said portion 57a and the plunger 57f. Preferably, said compression spring 57g must be relatively weak so that, when the printing ink is supplied to the cylindrical portion 57a from the container E through the conduit 57b via the flexible tubing 58 during a period in which the slider valve 30 is closed, the plunger 57f can be easily upwardly shifted by the pressure of the printing ink. However, the compression spring 57g facilitates, when the valve 30 is opened, the flow of the printing ink of even a relatively high viscosity through the passage of the valve 30 onto the ink receiving area on the screen 10.

The ink supply device 57 is preferably supported above the ink receiving area by means of an arm member 59 having one end integrally connected with an intermediate portion of the conduit 57b and the other end connected with the electromagnetic device 56 by means of a suitable fastening means such as a thumbscrew 60.

In the embodiments shown in FIGS. 16, 17 and FIG. 18, the hydraulic pump 54 includes an electrical motor (not shown) for operating said pump 54. This motor M may be electrically connected in the circuit for the apparatus as shown in the left-hand portion of FIG. 10.

In these embodiments shown in FIGS. 16 through 18, the container E is preferably provided with a plurality of wheels on the bottom thereof for facilitating transportation from one printing position to another or from one printing position to a room where the printing ink is prepared.

Although in the foregoing embodiments hereinbefore fully disclosed the slider valve 30 has been described as operable by the logical product of the electrical signals, one being fed from the switch DS (FIG. 10) of the liquid level detector 33 and the other being fed from the limit switch 32 or the switch LS of the electromagnetic device 49, it is to be noted that the opening of the passage of the slider valve 30 may be manually adjusted by

operating the adjustment screw 30j to supply the amount of the printing ink which corresponds to the amount of the printing ink that has been deposited on the cloth B to be printed, assuming that the latter amount is known. In this case, while the liquid level detector 33 may be omitted, the slider valve 30 should be arranged so as to be operable in response to each return of the squeegees 27a and 27b to the initial position or in response to each upward shift of the screen frame D during a period in which the squeegees are in the initial position.

Furthermore, it is to be noted that the liquid level detector 33 may be, instead of the ultrasonic and mechanical types hereinbefore described, a switching device 15 having a plurality of electrodes arranged so as to detect the deviation of the level of the surface of the printing ink relative to a predetermined level. In this connection, in the event that the printing ink has a relatively high viscosity so that the surface of said ink in the ink 20 receiving area may be rough, a switching device having three electrodes is recommended.

The carriage structure G (FIGS. 2 and 3) that has been described as having a supporter stud 21 with the lower end positioned adjacent to the floor or ground 25 and the other end substantially above the machine proper may be replaced by an over-head type as illustrated in FIGS. 19 through 22. If the over-head type arrangement is employed all of the containers E₁, E₂ and E₃ containing therein printing inks of different color 30 can be transported from their respective printing positions to an ink preparation room PR (FIG. 22) located a distance away from the machine proper.

As shown, the over-head type arrangement generally 35 includes two lengths of parallel mobile rails H₁ and H₂ extending in the lengthwise direction of the machine proper and suspended from a plurality of transversely extending fixed rails I₁ and I₂ for movement in the widthwise direction of the machine proper, said transversely extending fixed rails I₁ and I₂ being in turn suspended from the ceiling in the screen printing shop.

The mobile rail H₁ is adapted to carry a plurality of supporter studs 21' on rollers, each of said studs 21' having mounted on its lower end a container E₁, E₂ or E₃ positioned above the screen frame D in a manner 45 substantially the same as hereinbefore described. These supporter studs 21' are, as shown in FIG. 19, connected at their respective intermediate portion with each other by means of, for example, a chain H₃ and are movable in the lengthwise direction of the rail H₁. The other mobile rail H₂ is adapted to carry a hoist for suspending a mixing unit P and the hoist is movable in the lengthwise direction of the rail H₂ on a roller to enable the printing ink contained in each container E₁, E₂ and E₃ to be stirred thereby. This rail H₂ may be provided with an additional hoist (not shown) in a similar fashion to the hoist carrying the mixing unit P, for facilitating replacement of each container at the machine side or in the ink preparation room PR.

For preventing the containers E₁, E₂ and E₃ from rolling, an arm member Q may be provided which has a pair of spaced ends connected to respective vertical rods Q₁ and Q₂ which are in turn connected with the adjacent ends of the mobile rail H₁. The movement of the rails H₁ and H₂ may be effected by a chain belt J adapted to be driven by a geared motor K.

For transporting a train of the containers E₁, E₂ and E₃ from their respective printing positions to the ink

preparation room PR where one or more of the containers receive a supply of printing ink, a rail arrangement is provided such as shown particularly in FIG. 22. In other words, there is disposed a plurality of inner and outer loops, generally indicated by N and O, respectively, all of these loops N and O being connected to the adjacent ends of two fixed rails L₁ and L₂. The other ends of these fixed rails L₁ and L₂ are spaced a distance substantially equal to the length of either of the mobile rails H₁ and H₂ at one side of the machine proper. Of course, these loops O and N and fixed rails L₁ and L₂ are suspended from the ceiling of the screen printing shop.

From the foregoing description, it is clear that, when the mobile rail H₁ is brought into alignment with the fixed rails L₁ and L₂, a train of the containers can be transported from their respective printing position to the ink preparation room PR while being guided along these rails in a direction substantially parallel to the length of the machine proper. Alternatively, in the event that only one of these ink storage containers becomes empty, a vessel containing therein a substantial amount of printing ink to be supplied into the empty container can be brought to the proper position from the ink preparation room PR guided along either of the fixed rails L₁ and L₂ and then along the mobile rail H₂ which is at this time in alignment with the rails L₁ and L₂.

Preferably, each of the inner loops N in the ink preparation room PR is provided with at least two extra hoists, one for mixing and stirring the printing ink contained in the ink storage containers E and the other for facilitating the replacement of containers.

From the foregoing full description of the present invention, it will be clearly understood that the printing ink can be advantageously supplied in an automatic manner to compensate for the amount of said ink which has been consumed during the printing operation. In addition, the structure of the slider valve herein proposed is such that substantially no droplets of the printing ink will remain about the lower extremity of the passage of said valve after the supply of said ink onto the ink receiving area on the screen has been effected. However, it is to be noted that various modification and changes can be made which are apparent to those skilled in the art and therefore the present invention is not to be limited by the foregoing embodiments thereof. For example, a warning device such as signalling lamps or a buzzer may be provided for warning of the reduction of the amount of printing ink that is contained in the ink storage container when the level of the surface of the printing ink in the storage container arrives at a predetermined level. In this case, it is preferred to provide signalling lamps for each of the storage containers while a single buzzer is electrically connected with these lamps so that, when any one of these signalling lamps is lighted, the buzzer warns of the reduction of the printing ink in one of the storage containers. In addition, instead of the limit switch herein employed, a photosensitive detector comprising a photocell may be employed. In the latter case, the photocell should be arranged such that an electrical signal can be fed to the electromagnetic device only when the squeegee intercepts the path of the light beam incident to said photocell similar to the way that the limit switch is actuated.

Furthermore, for facilitating the manual adjustment of the opening of the slider valve, an access opening may be provided in the annular flange of each of the containers at a position adjacent to the adjustment screw of the slider valve.

In view of the fact that various changes and modifications of the present invention are apparent to those skilled in the art, they should be construed as included in the scope of the present invention unless otherwise departing from the true spirit and scope of the present invention.

What is claimed is:

1. An automated printing ink supply device for an automatic screen printing machine of the type including an endless belt adapted to be intermittently driven around a pair of drums for feeding material to be printed with the material adhered to the outer surface of said endless belt along a forwarding moving run thereof, at least one screen frame having a screen positioned above said endless belt, said screen frame being movable between an upwardly shifted position in which said screen is clear of said belt and a downwardly shifted position in which said screen is in contact with the material on the belt during the time the belt is stopped between intermittent movements, and a pair of juxtaposed squeegees reciprocally movable between first and second positions substantially across the width of the belt and slidable over the screen to deposit a printing ink contained on said screen between said squeegees, onto the material to be printed through said screen as said pair of squeegees is moved from either of said first and second positions to the other during the time the belt is stopped, said automated printing ink supply device comprising an ink storage container having an outflow opening and adapted to contain therein a substantial amount of printing ink, container mounting means positioned at one side of the machine on which said container is mounted at a position above the screen frame and squeegees and between the position of the squeegee remote from said mounting means when said squeegees are in the first position and said screen frame at said one side of said machine, a valve connected with said outflow opening of said container for regulating the flow of the printing ink from said container onto said screen, squeegee position and frame movement responsive means actuated in response to the presence of one of said squeegees adjacent to said mounting means upon return of said pair of said squeegees to said first position and further to the raising of said frame, means for detecting the level of the surface of said printing ink on said screen and producing a response when said level falls below a predetermined level, and valve operating means connected to said valve for opening and closing it and to which said squeegee position and frame movement responsive means and said level detecting means are coupled and operable to open said valve only when said responsive means is actuated and said level detecting means produces a response whereby said valve is opened only when the level of the surface of the printing ink on the screen falls below a predetermined level when the squeegees are at the said first position.
2. An automatic printing ink supply device according to claim 1, wherein said detecting means comprises an ultrasonic liquid level detector.

3. An automatic printing ink supply device according to claim 1, wherein said detecting means comprises an electrode type liquid level detector.

4. An automatic printing ink supply device according to claim 1, wherein said detecting means comprises a float type liquid level detector including a float adapted to float on the surface of said printing ink on said screen, and a limit switch adapted to be closed by said float only when said float descends beyond a predetermined position as the printing ink contained in said ink 10

receiving area is consumed.

5. An automatic printing ink supply device according to claim 1, wherein said opening of said valve is oriented toward the space between the pair of said squeezers.

6. An automatic printing ink supply device according to claim 1, wherein said mounting means is a carriage mounted on the side of said machine for movement therealong in the direction of the length of said belt.
